(57) **CLAIM**

The ornamental design for a dishwasher front panel, as shown and described.

DESCRIPTION

FIG. 1 is a right front perspective view of the dishwasher front panel;

FIG. 2 is a front elevational view thereof;

FIG. 3 is a right side elevational view with the left side being a mirror image thereof; and,

FIG. 4 is a top plan view thereof.

The broken line showing of a handle, mechanical indicators on the front panel and top panel, and the small, rectangular shape on the lower front door is included for the purpose of illustrating portions of the dishwasher front panel and forms no part of the claimed design.
